(57) **CLAIM**

The ornamental design for a carriage, as shown and described.

DESCRIPTION

FIG. 1 is a left, rear perspective view of a carriage showing my new design;

FIG. 2 is a right, rear perspective view of the carriage shown in FIG. 1;

FIG. 3 is a perspective front view of the carriage shown in FIG. 1;

FIG. 4 is a perspective front view of the carriage in FIG. 1;

FIG. 5 is a perspective left rear view of the carriage shown in FIG. 1;

FIG. 6 is a perspective right rear view of the carriage shown in FIG. 1;

FIG. 7 is a perspective (folded) view of the carriage shown in FIG. 1;

FIG. 8 is a (folded) rear view of the carriage shown in FIG. 1;

FIG. 9 is a (folded) top view of the carriage shown in FIG. 1; and,

FIG. 10 is a top view of the carriage shown in FIG. 1. Broken-line disclosure is understood to represent portions of the article in which the claimed design is embodied, but which form no part of the claimed design.
